UNITED STATES PATENT OFFICE.

ALBERT D. SIMMONS, OF CLEVELAND, OHIO.

METHOD OF PRODUCING A DECORATIVE WALL COVERING.

Application filed May 3, 1926. Serial No. 106,288.

My invention pertains to ornamentation, and is an improvement which consists in a method of producing a decorative covering for the interior walls of a building substantially as herein shown and described and more particularly pointed out in the claims. In general my object is to provide a method which will permit an artist or skilled craftsman to create and produce in a facile way a covering for walls and ceilings having an artistic design or ornamentation in relief and various colors, using a plastic medium having self-hardening properties and taking certain steps in sequence enabling the artist to stroke and remove portions of one or more coats of that medium while still elastic including parts of a sub-layer of the same medium which has attained a set or become hard previously. My improved method also permits such an ornate wall covering to be produced by hand in the shop or studio, the product possessing when finished, a decorated surface resembling stippled or hand modeled plaster, portions of the design being in relief or elevated and of different shade or color than the depressed portions. The decorated surface is hard although flexible in slight degree when the back or body of the product is made of woven fabric, such as canvas or duck, so that the finished product may be handled freely, and transported or shipped without damage or breakage, and mounted upon a finished interior wall or ceiling and permanently affixed thereto by any suitable adhesive or paste. A building wall so decorated embodies the actual hand work of the artist, but the cost and expense is greatly reduced and the work itself may be more artistically executed and expedited because made in the shop or studio and not under the handicaps and delays incident to building operations.

In the accompanying drawing, Fig. 1 is a front elevation of a small panel or piece of decorative covering made according to my improved method or process. Fig. 2 is a similar view, showing portions of the superposed layers or coatings of the design removed, and Fig. 3 is a sectional view of the product greatly magnified or enlarged.

In practicing this method of producing an ornamental or decorative wall covering, I prefer to use strips or sheets of woven material, such as a heavy canvas, as a base or mounting for the decorative surface. I may use other materials not as pliable or flexible

as canvas, but canvas or duck provides a strong and durable body having a woven surface to which a plastic medium such as I use will strongly adhere although the woven body is rendered less pliable and flexible by such medium when it sets and becomes hard. Thus, I first stretch the canvas A perfectly flat upon a flat board or base member B, using tacks 2 or any suitable means for fastening the edges of the canvas detachably in place. The exposed surface of the canvas is then treated to make it more or less impervious to the water contained in the compounds applied subsequently and the treatment also makes the surface smoother, as well as to prevent buckling or wrinkling during and after tooling operations. For that purpose I may give the woven surface a coat C of lead and oil paint, or one or more coats of any other suitable sizing compound comprising a pigment, lithopone, or a varnish. When the sizing coat is dry, I apply a coat or layer D of wet plastic compound smoothly thereto, for example a compound comprising a mineral base, casein and an alkaline substance, mixed with coloring matter and water to form a thick fluid, paste or plaster adapted to take a quick set and harden when dried. I do not limit myself to any specific composition, but the mineral base may be powdered talc, the casein may be treated with soda ash, and lime, alum and clay may be included. Another compound which may be used consists of a preponderating amount of powdered mica and china clay, a lesser amount of casein, and small amounts of borax, lime and oxide of zinc. The composition may be tinted, deeply colored, or plain white, and after a coat of this composition has been applied over the sizing coat it is allowed to dry, or is thoroughly dried by the application of heat, whereupon it becomes hard and stiff but sufficiently homogeneous to withstand bending in a limited degree without cracking or peeling.

Inasmuch as the composition has been mixed with water it will absorb a small amount of water after it has been dried, and this inherent property is advantageous in practicing the next steps in the method or process, which consists in applying a second coat E of the same compound, but in a contrasting tint or color, upon the previous coat. In some instances the first composition coat or layer may be smoothly finished

by sand paper, or it may be stippled or tooled with a design before it has fully hardened. The second composition coating covers the first completely and a part of its water content penetrates the hard surface of the first coating to some extent and tends to soften the same so that both the top and bottom composition coatings may be tooled together in the following manner: Thus before the second or top coating sets or becomes hard and while it is still wet and sticky any desired ornamental design or artistic representation is outlined on the top surface, preferably by laying a perforated paper pattern of the design upon the top coat and pouncing charcoal through this perforated sheet. The top coat, being wet and more or less sticky, a thin coat of dry powder is dusted or lightly applied over the top surface. This powder is preferably made of the same materials as the top coat itself. The perforated paper pattern may then be removed without tearing it where weak or closely perforated. The artist then reproduces the design by removing portions of the top composition coat while it is still soft, using various tools and instruments adapted to scrape and lift the moist material apart from the bottom coating which is harder and of a different tint or color. By applying sufficient pressure to the tool, for example a tool as delineated having a wire loop 3 to scrape the compound free, a portion 4 of the bottom coating or layer is skinned or removed in addition to the top layer, due to the softening influence of the water absorbed from the top coat, thereby effacing in substantial degree the top coat or layer of different color and producing hand tool marks with embellishing effect in the bottom layer of contrasting color. The parts of the top coat which are not scraped are homogeneously united with the bottom layer and this part of the design is displayed in bold relief in contrasting color to the depressed design or sunk figure, and both small and large sunken areas are involved dependent upon the artistic effect to be produced, even to fine lines and scratches corresponding to finely etched surfaces. In producing a large design or in working on large areas it is necessary to cover the un-worked area with a damp cloth to prevent the second coating or layer of composition materials from hardening, thus retarding the solidifying tendencies of the composition in part while the artist uses the etching tool on the uncovered plastic portions of the work. When the design is completed the entire decorated surface may be trimmed, and affixed at any time to the surface to be decorated.

Additional steps may be taken to produce a more elaborate design involving many different colors, by repeating the steps either

in part or whole as hereinbefore described. For example, after the second coat has been applied and portions thereof removed to produce a design in relief in two colors, one or more additional coatings of the same composition but of different tints or colors may be applied and tooled in the same way to uncover portions of the tooled design underneath. The plastic material may be applied by a brush and a finishing effect obtained by trowel, hand or other device, and portions of one treated surface may be built up and worked in two or more colors without necessarily carrying the same design and combination of colors throughout the entire decorated area. For example, say a double layer of the desired composition has been applied to the canvas backing and a design or ornamental figure has been developed in relief in contrasting colors as described, I may apply a third coat of the same composition in a still different tint or color to either the raised figure or to the depressed figure, or additional different layers to each, and then tool and remove portions of the third coat in the same way as described, thereby obtaining a multi-colored design or figure with the contrasting parts thereof at various elevations or in variable relief. Finally a protecting coating of varnish or clear lacquer may be applied to the tooled surface after the composition product has hardened, if desired.

What I claim, is:

1. A method of producing a pliable decorative wall covering, consisting in superposing separate water-mixed plastic coatings of self-hardening compositions of different color and softenable by water upon a flexible base member and in removing portions of the top and lower coats while said top coat is still plastic and while the lower coats are slightly softened by water of the top coat entering into said lower coats to produce a vari-colored design in relief thereon.

2. A method of producing a pliable decorative wall covering, consisting in applying a water-resisting material to a woven fabric, in applying a water-mixed plaster composition having hardening properties and softenable by water over said coating and drying the same; in applying a second water-mixed coating of plastic composition having hardening properties over said first plaster coating; in tooling a design in relief in said superposed coatings after the water of said second coat has slightly softened said first coat by removing plastic portions of said coatings from each other and their common base; and finally drying and hardening said tooled surfaces.

3. A method of producing a pliable decorative wall covering, consisting in superposing separate coats of self-hardening water-mixed plastic compounds of different

color upon a woven fabric covered with a water resisting material and while the top coat is still wet and plastic and the lower coats softened by the water of the top coat, applying a thin coat of dry powder over the top coat in laying a perforated pattern of a design thereon; in pouncing colored powder through said pattern; and in tooling the wet top coat and the lower softened coats on the lines of the pounced design. 10
In testimony whereof I affix my signature.

ALBERT D. SIMMONS.
